UNITED STATES PATENT OFFICE

162,925

DEVICE FOR DISPLAYING AXES OR OTHER ARTICLES OF MERCHANDISE

David E. Berkowitz, Elkins Park, Pa.

Application April 14, 1950, Serial No. 9,193

Term of patent 7 years

(Cl. D80—10)

To all whom it may concern:

Be it known that I, David E. Berkowitz, a citizen of the United States, residing at Elkins Park, county of Montgomery, State of Pennsylvania, have invented a new, original, and ornamental Design for a Device for Displaying Axes or Other Articles of Merchandise, of which the following is a specification, reference being had to the accompanying drawings, forming a part hereof.

Figure 1 is a front perspective view of a device for displaying axes or other articles of merchandise showing my new design.

Figure 2 is a front elevational view.

Figure 3 is an elevational view looking from the side of Figure 2.

Figure 4 is a plan view looking from the top of Figure 3.

The broken lines showing an axe in Figure 1 are for illustrative purposes only.

I claim:

The ornamental design for a device for displaying axes or other articles of merchandise, as shown and described.

DAVID E. BERKOWITZ.
